UNITED STATES PATENT OFFICE.

EDWARD T. MALONE, OF LACKAWANNA, NEW YORK.

HAND TRUCK.

Application filed April 22, 1922. Serial No. 555,979.

To all whom it may concern:

Be it known that I, EDWARD T. MALONE, a citizen of the United States, residing at Lackawanna, in the county of Erie and State of New York, have invented certain new and useful Improvements in Hand Trucks; and I do hereby declare the following to be a full, clear, and exact description of the invention, such as will enable others skilled in the art to which it appertains to make and use the same.

This invention relates to hand trucks, and more particularly to hand trucks such as are commonly used for conveying boxes and barrels.

The object of the present invention is to provide a hand truck of an improved construction embodying means enabling it to be used on stairs or similar structures and also embodying novel features for readily securing the packages upon it.

The invention consists in the novel construction, arrangement and combinations of parts as hereinafter more particularly described and claimed.

Two sheets of drawings accompany this specification as part thereof, in which like reference characters indicate similar parts throughout.

Figure 1 is an elevation view of the improved truck;

Fig. 2 is a detail fragmentary view taken in section on the line 2—2 of Fig. 1;

Fig. 3 is a fragmentary detail view taken in section on the line 3—3 of Fig. 1;

Fig. 4 is a fragmentary detail view taken in section on the line 4—4 of Fig. 1;

Fig. 5 is a side elevation of the improved truck;

Fig. 6 is a detail fragmentary view taken in section on the line 6—6 of Fig. 5, and

Fig. 7 is a detail fragmentary view taken in section on the line 7—7 of Fig. 5.

In accordance with the present invention, a frame 1 is provided which is of substantially rectangular form and preferably made from bar metal or metal tubing. One end 2 of this frame is bent perpendicularly to the main frame to provide a heel. Hangers 5—5 consisting of sheet metal bent snugly around the sides of frame 1 and having their depending parts welded or otherwise secured together, carry a main axle 3 and a secondary axle 6 above and in spaced relation to the main axle. Upon the main axle 3 are mounted wheels 4 exteriorly of

the frame while within the frame, but adjacent thereto on either side or elsewhere intermediate the frame parts as may be desired, are secured frame guides 7 which may be of U-shaped cross section as here illustrated or other suitable shape as may be desired, and which, as indicated, may be provided in any number or particular position relative to the frame as may be desired. Further, these frame guide members 7 may be straight and parallel with the side members 1 of the frame or they may be bent as illustrated in Fig. 5, or otherwise to suit the purposes to which the particular truck is to be applied. These frame guide members 7 are secured upon the shafts 3 and 6 by having their ends bent up and over these shafts as is illustrated in Fig. 5, and indicated in Figs. 6 and 7. Upon these frame guides 7 are mounted endless chains 9, formed of a plurality of links 10 united by pins 18 upon which a tread or facing 11 of leather, rubber or other suitable material is supported. Pins 18 are pivoted adjacent the inner edge 80 of links 10 and are further provided with rollers 19 which are adapted to contact with the face of guide 7 as is well illustrated in Fig. 7.

Sliding upon the side members 1 of the main frame and above the auxiliary axle 6 is a transverse supporting member 12 slideable upon the frame and secured thereto by having its ends bent over and around the frame loosely as at 13. One end is further provided with an extending lug 14 bent downwardly as illustrated in Fig. 2, and provided with a slot 15 adapted to receive the links of a chain 16 to secure the same, the other end of the chain 16 being provided with a U stirrup member 17, the legs of which are adapted to straddle the member 12 and to be bent around the frame member 1 loosely on either side of member 12 so that it will be moved upon the frame 1 by movement of the part 12 simultaneously therewith.

In operation, the barrel or other article to be conveyed is lifted upon the heel 2, thrown backward to rest against the brace 12 which is positioned on frame 1 at a convenient height for the particular article, whereupon the chain 16 is passed over the barrel and pulled tight, the link then adjacent to slot 15 being passed into said slot to secure the same in position. Upon a level surface the truck operates upon wheels 4

as is customary, but upon ascending or descending stairs the endless chains 9 will come into operation as is well illustrated in Figure 5.

5. Modifications in the precise details of construction and arrangement of parts will readily suggest themselves to those skilled in the art, but all within the scope of the present invention.

10. I claim:

1. In a hand truck having a frame consisting of parallel side members, a transverse axle and supporting wheels mounted on the axle, guide frames supported directly 15 from the axle and the frame and endless tread parts slidably mounted on the guide frame.

2. In a hand truck, a skid device comprising a guide frame extending longitudinally 20 of the truck and directly from the axis of the truck wheels being spaced from and below the frame and an endless tread slidably mounted on said guide frame so as to contact its lower face.

25. 3. In a hand truck, a skid device comprising a guide frame of U-shaped cross section having its ends bent arcuately in the same direction and away from the flanged face to provide pivots and an endless chain tread

slidably mounted on said guide between its 30 flanges and extending over its upturned ends, said guide frame being supported from the truck frame through said arcuately bent ends.

4. A hand truck comprising in combination, a frame having side members, an axle, a supplementary axle, wheels mounted on the axle, skid guide frames extending between the axle and the supplementary axle, endless tread members slidably mounted on 40 the skid guide members, and adjustable securing means for securing the load in position on the truck.

5. In a hand truck of the class described having parallel side frame members, a 45 transverse supporting member slidable longitudinally on the side frame members, a chain having one end slidably secured to one side frame member in association with the transverse supporting member and 50 means for interlocking the free end of the chain with the other end of the transverse supporting member comprising an outwardly extending slotted lug formed on said supporting member whereby the load may be 55 firmly secured to the truck.

In testimony whereof I affix my signature.
EDWARD T. MALONE.
